(57) **CLAIM**

The ornamental design for a dish rack, as shown and described.

DESCRIPTION

FIG. 1 is a top, front, right-side perspective view of a dish rack showing my new design;

FIG. 2 is a top, rear, left-side perspective view thereof;

FIG. 3 is a bottom, rear, right-side perspective view thereof;

FIG. 4 is a front elevational view thereof;

FIG. 5 is a rear elevational view thereof;

FIG. 6 is a left-side elevational view thereof;

FIG. 7 is a right-side elevational view thereof;

FIG. 8 is a top plan view thereof; and,

FIG. 9 is a bottom plan view thereof.

The broken lines shown in the drawings depict portions of the dish rack that form no part of the claimed design.
